UNITED STATES PATENT OFFICE.

LEE SHOWERS, OF CHARLEROI, PENNSYLVANIA, ASSIGNOR TO PITTSBURGH PLATE GLASS COMPANY, A CORPORATION OF PENNSYLVANIA.

PROCESS AND APPARATUS FOR ROLLING PLATE GLASS.

Application filed January 29, 1927. Serial No. 164,482.

The invention relates to a process and apparatus for rolling glass sheets intermittently between a pair of rolling members, such as those shown in my Patent No. 1,579,-
5 666 issued April 6, 1926, and particularly to a process and means for confining the ends of the body of molten glass which is poured into the pocket between the rolling members. In the operation of an apparatus, such as that
10 specified, there is a tendency for the glass to flow somewhat unevenly through the pass between the rolls, and the edges formed, due to the chilling effect of the triangular metal confining means (sometimes called guns) at
15 the ends of the body of glass, are often very rough. Further, the chilled edge portions of the sheet, which must be trimmed off, often extend inward several inches, thus involving a considerable loss in production. The present
20 invention is designed to overcome the difficulties above set forth and to provide means (1) for holding back the body of glass in the pocket between the rolls, so that it flows down uniformly and evenly through the pass between the rolls; and for securing edges upon the sheet which are less rough than those heretofore secured and in which the chilled portions requiring trimming extend back a less distance into the sheet. A further result secured by the improvement is the speeding up of the operation, incident to the use of the removable plates which lie in front of the closure members at the ends of the pocket carrying the body of molten glass, this expedient permitting the casting operations to follow each other in quick succession. Certain embodiment of the invention are illustrated in the accompanying drawings, wherein:
30 Figure 1 is a partial vertical section through the apparatus. Fig. 2 is a partial plan view. Fig. 3 is a section on the line III—III of Fig. 1. Fig. 4 is another section on the line III—III of Fig. 1, but on a larger scale. And Figs. 5 and 6 are details showing a modified construction.
40 Referring to the drawings, 1 is an annular casting or rolling member supported upon a pair of driven rolls 2, 2, and 3 is a sizing roll, preferably water cooled and supported in a suitable framework 4. This framework is adjustable by means of the pivoted screws 5 for swinging the brackets 6 up and down and so regulating the distance between the roll 3 and the rolling member 1. The apparatus as

just described is shown only in a diagrammatic way and requires no further explanation in view of the full disclosure in my patent heretofore referred to, it being understood that the rolls 2, 2 are driven and so drive the 60 rolling member 1, and that the sizing roll 3 is driven in any suitable manner.

The pocket or recess between the rolling members is adapted to receive a pot of glass and this pocket is closed at its ends by means 65 of the cast steel retaining members 7, 7 secured together at their rear ends by a cross tie 8^a which is in the form of a commercial angle rests upon the surface of the member 1. The members 7, 7 also rest upon the surface 70 of the member 1 and engage the periphery of the roll 3 at their forward ends. Removably carried by the closure members 7, 7 are a pair of steel plates 8, 8 each provided with a pair of brackets 9, 9, each extending over the upper edges of the members 7, 7 and fitting removably into vertical recesses 9^a, 9^a in the members, as indicated in Fig. 3. These brackets are bent so as to form eyes 10, 10 at their upper edges so that they may be engaged by a suitable hook for positioning the plates and for removing them. As shown, the plates are provided with the inwardly projecting spikes 11. If the plates are made in the form of castings, these spikes are integral with the plates, but if the plates are formed from rolled sheets, the spikes will be made separately and fitted through perforations in the plate.

The plates are so proportioned that, when 90 hung in position, as indicated in Fig. 1, the lower curved edges 12 of the plates are spaced away a short distance from the periphery of the rolling member 1. This distance is greatest at the point 13 (Fig. 1) and gradually decreases until the rear ends of the plates are reached, at which point the plates touch the periphery of the roll.

In operation, the plates 8, 8 are preliminarily heated to a red heat in a separate furnace and then positioned, as shown in Figs. 1 and 2 by means of suitable transfer devices which engage the hooks 10, 10. As soon as these plates are positioned, a pot of glass is cast into the pocket between the rolls 1 and 3, 100 such rolls being driven at such time in the direction indicated by the arrows. The body of glass A in the pocket immediately adheres to the spiked inner surfaces of the hot plates 8, 8, the use of the plates in pre-heated con- 110

dition facilitating the attachment of the glass to the plates. However, even if the plates are not pre-heated, the glass will attach itself to the plates, since the heat of the body of glass 5 is sufficient to bring the plates up to a red heat so that the glass will weld thereto. This adhering action, however, does not occur so readily if the plates are not pre-heated and for that reason it is preferred to pre-heat the 10 plates. The attachment of the glass to the plates 8, 8 serves to hold back the body of glass at its side edges and experience has shown that under such conditions, the feed of glass between the rolls in much more uniform and 15 steady than if there is no attachment of the glass to the metal closure members at the ends of the pocket. The rolling operation of the body of glass is continued until such glass is entirely exhausted. In order to prepare the 20 rolls for new casting operation, the plates 8, 8 are removed and a new set of pre-heated plates brought from the furnace and positioned upon the members 7, 7 as heretofore described so that a new pot of glass may be 25 cast immediately. The plates 8, 8 after removal from the members 7, 7 may be allowed to cool, after which the cold glass may be readily cracked off, or the plates may be thrust into a bath of water and cooled quickly to 30 cause the glass to crack away. The plates may then be reheated in the furnace preliminarily to further use. The use of removable plates 8, 8 not only serves to improve the rolling operation for the reason heretofore set 35 forth, but also adds to the convenience and speed of operation of the apparatus, since there is very little delay between casting operations, such as would occur if the glass came directly in contact with the members 7, 7 and 40 adhered thereto, thus requiring the expenditure of considerable time after each operation in cleaning the members.

The provision of the spaces between the lower edges 12 of the plates 8, 8 and the 45 periphery of the rolling member 1 has been found to improve the edges formed upon the glass sheet, the chilled edges being smoother and calling for less width in trimming than when the spaces beneath the edges 12 are not 50 provided. This is apparently due to the fact that the glass which forms the edges of the sheet flows out into the spaces beneath the edges 12 and is chilled by direct contact with the members 7, 7 so that these edges do not 55 adhere either to the members 7, 7 or the plates 8, 8 and are consequently smoother and better formed than if they had adhered to a metal body and been pulled loose therefrom.

Figs. 5 and 6 illustrate a modification in 60 which removable plates 14 take the place of the plates 8 of the Fig. 1 construction. These plates are supported by brackets 15 corresponding to the brackets 9 and the construction is in other respects similar to that of 65 Fig. 1. The plates 14 differ from the plates 8

in that the spikes 11 of the first construction are omitted and in place thereof, the plates are provided with the perforations 16. These perforations preferably taper inward, as indicated in Fig. 6, and when the body of glass 70 is cast into the pocket, such glass flows into the recesses 16, as indicated in Fig. 6, so that a holding effect is secured by the recesses quite similar in effect to the holding effect of the spikes 11. The construction of Figs. 5 75 and 6 has an advantage over that of Fig. 1 in that the plates may be used indefinitely without replacement or repair, which is not the case with the plates of the Fig. 1 construction, wherein the spikes are oxidized and broken away more or less in the course of time. This breaking away of the spikes has the further disadvantage that the particles of iron remaining in the cold glass, which becomes cullet, is incorporated into the new 80 glass when remelted and tends to discolor it somewhat. This disadvantage does not obtain in the case of the construction of Figs. 5 and 6, wherein there are no projecting parts to break away. In both forms of construction, the old glass is readily removed from the plates when they are cooled.

While the process is preferably practiced by the use of the removable plates imposed over the closures 7, 7, it is quite possible to dispense with the plates, and allow the glass to come directly in contact with the members 7, 7, which would exercise the same holding effect upon the body of glass, if pre-heated and provided with spikes or recesses, 95 so that in its broadest aspect the process is not limited to the use of the removable face plate 8, 8. However, the use of preheated members 7, 7 is less advantageous, because of the greater difficulty in removing and re-heating them, which would slow up the operation, and because of the greater difficulty in 100 cleaning off the adhering glass.

What I claim is:

1. The combination with a pair of opposing horizontal rolling members, having a pocket therebetween for receiving a body of molten glass to be rolled into a sheet, of closure members fitting between the rolls and constituting the ends of the pockets and removable sheet metal plates fitting the inner faces of said closure members. 110

2. The combination with a pair of opposing horizontal rolling members, having a pocket therebetween for receiving a body of molten glass to be rolled into a sheet, of closure members fitting between the rolls and constituting the ends of the pockets and removable sheet metal plates fitting the inner faces of said closure members, and provided over their inner faces with recesses for increasing the holding effect of the plates upon the glass. 120

3. The combination with a pair of opposing horizontal rolling members, having a 130

5 pocket therebetween for receiving a body of molten glass to be rolled into a sheet, of closure members fitting between the rolls and constituting the ends of the pockets and re-
movable preheated sheet metal plates lying on the inner sides of said closure members.

4. The combination with a pair of opposing horizontal rolling members, having a pocket therebetween for receiving a body of
10 molten glass to be rolled into a sheet, of members at the ends of the pockets comprising sheet metal plates for engaging the glass and adapted to adhere thereto when heated, and means for supporting the plates removably
15 in position.

5. The combination with a pair of opposing horizontal rolling members, having a pocket therebetween for receiving a body of molten glass to be rolled into a sheet, of closure members fitting between the rolls and constituting the ends of the pockets and removable sheet metal plates fitting the inner faces of said closure members, the lower edges of said plates being spaced above the periphery of the lower rolling member a slight distance
20 of said plates being spaced above the periphery of the lower rolling member a slight distance.
25

6. The combination with a pair of opposing horizontal rolling members having a pocket therebetween for receiving a body of molten glass to be rolled into a sheet, of closure members fitting between the rolls and constituting the ends of the pockets and removable sheet metal plates fitting the inner faces of said closure members, the lower edges of said plates being spaced above the periphery of the lower rolling member a slight distance at their forward ends, and gradually approaching said periphery from such point back.
30

7. The process of rolling glass sheets between a pair of rolling members, which consists in providing removable end closures for the casting pocket between said members, pouring a body of molten glass into the pocket, causing it to adhere to said closures, rolling said body into a sheet, and after such operation removing said closures and repeating said operations.
35

In testimony whereof, I have hereunto subscribed my name this 3rd day of January, 1927.
